METHOD OF FORMING BRAKE DRUMS OR
LIKE STRUCTURES

Charles S. Ash, Milford, Mich., assignor to Kelsey-Hayes Wheel Company, Detroit, Mich., a corporation of Delaware

Application December 17, 1934, Serial No. 757,959

6 Claims. (Cl. 29—152.2)

The invention relates to the manufacture of brake drums and similar structures from sheet metal blanks of uniform gauge. It is the object of the invention to form from such a blank a structure having different portions thereof of varying thicknesses and more particularly to form the cylindrical flange for the braking surface of greater thickness than the web portion of the drum. To this end the invention consists 5 in the method and apparatus as hereinafter set forth.

In the drawings:

Fig. 1 is a cross section through an apparatus for bowlng a blank of uniform gauge to form 15 a web and substantially cylindrical flange;

Fig. 2 illustrates the manner of upsetting the flange portion of the blank to increase the thickness thereof;

Figs. 3 and 4 illustrate successive steps of forming a peripheral flange at the end of the cylindrical portion of increased thickness;

Figs. 5, 6, 7, 8 and 9 are views similar to Figs. 1 to 4 illustrating a modified method;

Figs. 10, 11, 12 and 13 are enlarged views illustrating the upsetting operation;

Fig. 14 is a diagrammatic view illustrating the geometrical principle involved in the modified construction illustrated in Figs. 5 to 10.

In the manufacture of drums from sheet metal 30 blanks of uniform gauge, the usual method is to first cut a circular blank from the sheet metal, then to bowl this blank by the operation of dies or other means to form a web portion and a cylindrical flange. During this bowlng operation the diameter of the peripheral portion of the blank is contracted, which may result in a slight upsetting or thickening of the gauge. However, as generally performed, the metal flows to increase the length of the cylindrical flange instead of increasing the thickness. In other words, the measurement of the cross sectional contour from the center of the bowlng blank to the outer edge of the cylindrical flange would show an increase in length over the radius of the original flat blank. For use in brake drums it is desirable to have a greater thickness in the cylindrical flange than is required for proper strength in the web portion of the drum. However, as above described, this increase in thickness is not 40 obtained by the usual method of bowlng the blank. Consequently the amount of metal used and the weight of the drum are greater than required for proper strength, inasmuch as it is essential that the brake flange should be of the proper thickness.

To overcome this defect I have devised a method and apparatus through which the thickness of the flange portion of the bowlng blank may be increased over the thickness of the web portion as follows:

As shown in Fig. 1, a heated circular sheet metal blank A is placed over a conical female die member B terminating in a cylindrical portion C. The plunger D then presses the blank A into the die B, bowlng the same as indicated 5 at E, Fig. 1. The bowlng blank is then reheated and transferred into engagement with the cylindrical female die F and the web portion is clamped by a male die G, leaving sufficient space 10 between the concentric cylindrical surfaces F' and G' for the increased thickness of flange 15 which is desired. An annular die H is then forced into the space between surfaces G' and F' engaging the end of the flange of the bowlng blank E and compressing and upsetting the same 20 until it is enlarged in thickness to correspond to the space between said surfaces F' and G'. It 25 will be understood that the diameter of the original flat blank is so selected as to obtain the desired length of the thickened cylindrical flange 25 E' after the upsetting operation.

The blank with the thickened flange E' is then subjected to die operations illustrated in Figs. 3 and 4 which form thereon an outwardly extending peripheral flange E².

With the construction as above described, the upsetting of the blank is effected in a chamber or space between the dies which is equal in radial dimension to the thickness of the finished flange. However, during the upsetting operation this 35 space is greater than the thickness of the flange so that there is nothing to restrain the latter from wrinkling. To overcome this objection I have devised a construction and a modified method in which the chamber for receiving the 40 thickened flange is increased in radial depth just in proportion to its diminution in length so that during the entire upsetting process the inner and outer surfaces of the blank are in contact with the corresponding surfaces of the die. The apparatus shown in Figs. 5 to 9 is similar in general construction to that illustrated in Figs. 1 to 4, but in place of spaced dies which are exactly 45 cylindrical between which the flange of the blank is upset, I employ dies which are slightly conical. 50 The amount of taper of these conical dies is so selected that by moving the outer die downward with the upsetting member, the space between this die and the inner conical member will be radially enlarged just in proportion to the in- 55

- crease in thickness of the metal due to upsetting. In other words, the volume of the space between the conical dies which is occupied by the blank remains constant during the upsetting operation 5 although it is diminished in length as it is increased in radial depth. This is illustrated diagrammatically in Fig. 14 in which the rectangle a, b, c, d represents the cross section of a blank before upsetting and e, f, c, g is a rectangle of 10 equal area but of diminished length and increased thickness. h is the point of intersection of the lines $a-b$ and $e-g$, and it will be understood that the line $a-h$ is equal to the amount of contraction in length and the line $e-h$ is equal 15 to the amount of increase in width during change from the rectangle a, b, c, d to the rectangle e, f, c, g . By connecting the points $a-e$ by a straight line and then moving the right angle $d-a-b$ with its apex a in the line $a-e$ and its 20 sides $a-d-a-b$ maintained parallel respectively to their original position, there will be no change in area of the rectangle but it will be progressively decreased in length and increased in width. 25 This principle is further illustrated in Figs. 12 and 13 in which I is an inner conical die member and J is an outer conical die member which are movable in relation to each other along a common axis parallel to the line K-K. In Fig. 12 30 the space between these die members is of a length and width equal to the length and thickness of the blank before upsetting and in Fig. 13 the length has been shortened and the width increased to correspond to the upset blank. At 35 each point during the movement, the cross section of the blank will remain constant and its sides will be in contact with the sides of the dies I and J.
- With the apparatus shown in Figs. 5 to 11, the 40 principle is the same as that shown in Figs. 12 to 14, but to facilitate the operation, the periphery of the bowled blank has first formed thereon a radial flange which is clamped between die members. Fig. 5 illustrates the first operation of 45 bowling the blank to form a substantially cylindrical flange L terminating in an outwardly flaring flange L'. In Fig. 6 this bowled blank is further pressed in dies to flatten the flaring flange L' into a radially extending flange L² to also re- 50 fashion the web portion of the blank as indicated at M and to change the cylindrical portion L into a slightly coned portion as indicated at N. The blank is then upset as shown in Figs. 7 and 8, and enlarged views 10 and 11 the flange L² be- 55 ing clamped between die members O and O' which together move downward in relation to the central die members P and Q between which the web of the blank is clamped. The operation will be the same as shown in Figs. 13 and 14 resulting 60 in an upset, thickened and slightly tapered flange R. The blank is then refashioned as shown in Fig. 9 to change the tapered flange R into a cylindrical flange R'.
- What I claim as my invention is:
- 65 1. A method of forming brake drums or like structures comprising the cutting of a blank from sheet metal of uniform gauge, bowing said blank to form the web portion and flange portion of the drum and applying endwise upsetting pressure to 70 the flange portion to reduce the length and uni-

formly increase the thickness throughout its length.

2. The method of forming brake drums or like structures comprising cutting a blank from sheet metal of uniform gauge, said blank being of a 5 mass equal to that of the fashioned drum, and of a diameter greater in measurement than the cross sectional contour of the fashioned drum, bowing said blank to form a substantially cylindrical flange of greater length than in the fashioned 10 drum, and endwise compressing said flange to upset the same, reducing its length and uniformly increasing its thickness throughout its length.

3. The method of forming brake drums or like structures comprising cutting a blank from sheet metal of uniform gauge, said blank being of a mass equal to that of the fashioned drum and of a diameter greater in measurement than the cross sectional contour of said fashioned drum, bowing 20 said blank to form a substantially cylindrical flange of greater length than in the fashioned drum, placing the bowled blank with its flange between concentric dies and endwise compressing said flange while between said dies to reduce its 25 length and uniformly increase its thickness throughout its length.

4. The method of forming brake drums or like structures comprising cutting a blank from sheet metal of uniform gauge, said blank being of a 30 mass equal to that of the fashioned drum and of a diameter greater in measurement than the cross sectional contour of said fashioned drum, bowing the blank to form a substantially cylindrical flange, placing the bowled blank between 35 dies having concentric portions with a space therebetween equal in length and radial depth to the flange of the bowled blank and relatively moving said dies to simultaneously diminish the length and increase the radial depth of said space 40 while maintaining a substantially constant cross sectional area.

5. The method of forming brake drums or like structures comprising cutting a blank from sheet metal of uniform gauge, said blank being of a 45 mass equal to that of the fashioned drum and of a diameter greater in measurement than the cross sectional contour of said fashioned drum, bowing said blank to form a substantially cylindrical flange thereon of greater length than in the 50 fashioned drum, endwise compressing said flange to diminish the length thereof, holding said flange during said upsetting operation between outer and inner die members and relatively moving said outer and inner die members during said 55 upsetting operation to increase the space therebetween proportional to the diminished length of the flange to maintain at all times a substantially equal cross sectional area.

6. In a method of forming brake drums and like structures from sheet metal blanks, the step of holding the flange portion between dies having portions contacting the opposite sides and opposite ends thereof and moving said dies to increase the distance between the sides and diminish the distance between the ends thereof maintaining at all times a uniform cross section and thereby uniformly increasing the thickness and diminishing the length of said flange.
